DESIGN FOR A CULOTTE DRESS OR SIMILAR ARTICLE

Tina Leser, New York, N. Y.

Application October 6, 1945, Serial No. 122,616

Term of patent 3½ years

(Cl. D3—26)

To all whom it may concern:

Be it known that I, Tina Leser, a citizen of the United States, residing in New York city, in the county of New York and State of New York, have invented a new, original, and ornamental Design for a Culotte Dress or Similar Article, of which the following is a specification, reference being had to the accompanying drawing, forming part thereof.

Fig. 1 is a front view of a culotte dress or similar article, showing my design;

Fig. 2 is the rear view of the culotte dress or similar article shown in Fig. 1;

Fig. 3 is a fragmentary front view of the culotte dress or similar article shown in Fig. 1, illustrating the leg portions in expanded position, and

Fig. 4 is a fragmentary rear view thereof in partially unbuttoned condition.

I claim:

The ornamental design for a culotte dress or similar article, substantially as shown.

TINA LESER.
